DISPLAY APPARATUS.

1,222,091.

Specification of Letters Patent. Patented Apr. 10, 1917.

Application filed March 16, 1914. Serial No. 824,914.

To all whom it may concern:

Be it known that I, WILLIAM A. FRICKE, citizen of the United States, residing at Oak Park, in the county of Cook and State 5 of Illinois, have invented a certain new and useful Improvement in Display Apparatus, of which the following is a full, clear, concise, and exact description, reference being had to the accompanying drawings, forming 10 a part of this specification.

My invention relates to display apparatus of the class including display boards formed of many collocated electrically controlled display elements preferably in the form of 15 electric lamps, though the invention is not to be limited to the nature of the responsive devices which are to constitute the display elements. In such apparatus switching or transmitting boards have been employed that 20 were made of a plurality of circuit terminals individual to the display elements and usually similarly collocated.

In practising my present invention the above described equipment of the prior art 25 may be used and in conjunction with this equipment electro-magnets are employed that are included in circuits which are individual to the display elements and their similarly collocated contact terminals and 30 which magnets are provided or associated with means for enabling the maintenance of the display elements in set display condition whereby any selected plurality of display elements may simultaneously coöperate to 35 present a signal, character, or emblem. In the preferred embodiment of the invention the magnets perform their function when they are energized and serve to close normally open circuits that include the display 40 elements. In this arrangement the magnets are desirably provided with locking circuits which are closed by the energized magnets through their windings whereby the magnet armatures are maintained in the positions to 45 which they are attracted then to maintain the operated display elements in set display condition. Means are provided for restoring such operated display elements one by one or simultaneously as desired.

50 My equipment preferably includes electro-magnets supplied in addition to the aforesaid electro-magnets and also individual to the display elements for effecting their operation and maintaining them in display condition only while the energizing circuits for

these latter magnets are closed at circuit terminals upon the switching or transmitting boards, these latter magnets having no means for maintaining their energization when their energizing circuits are broken at 60 the corresponding transmitting board terminals. In the preferred form of equipment certain of the display elements may be maintained in set display condition by those of the first aforesaid magnets that are individual thereto while other display elements may be placed in non-set display condition by those of the second aforesaid magnets that are individual to these latter display elements. 65

I will explain my invention more fully by reference to the accompanying drawing showing the preferred embodiment thereof and in which Figure 1 is a diagrammatic view illustrating one circuit arrangement 75 and in Fig. 2 is a diagram illustrating the mechanical interrelation of the transmission and receiving boards. 70

Like parts are indicated by similar characters of reference in both figures. 80

The transmitting board includes a plurality of terminals 1 each individual to a display element 2. These display elements are desirably in the form of electric lamps but are not to be limited to such an embodiment. The contact terminals 1 and the responsive devices 2 individual thereto are preferably similarly distributed on their respective boards, though the area occupied by the transmitting board may, if desired, 90 be quite small as compared with the area occupied by the display board. Each contact terminal 1 has a complementary contact terminal which is desirably common to all of the contact terminals 1 and in such event 95 may be embodied in a stylus 3. The circuit arrangements for all of the lamps or responsive devices 2 are desirably similar, each circuit arrangement including a contact 1 and the complement thereof such as the stylus 3. 100

Referring now more particularly to Fig. 1, a circuit is established whenever the stylus 3 is applied to any of the contact buttons 1, which circuit may be traced from the touched button 1, the intermediate armature 105 switch of the relay 4 (each lamp 2 having a relay 4 individual thereto) the normal contact of this armature switch, the normally engaged contacts 5 and 6, the winding of relay 7, (each lamp 2 having a relay 7 110

individual thereto) the battery or other suitable source of current 8, thence to the stylus 3 in contact with the touched button 1. The relay 7 is thereupon energized and is permitted to remain energized if the display is to remain set owing to the establishment of a locking circuit by this relay and which locking circuit is traceable from the positive pole of the battery 8, the omnibus restoring key 9, the left hand armature switch of relay 4 and its normally engaged contact, the intermediate armature switch of relay 7 and the contact 6 then engaged thereby, the winding of relay 7, thence back to the battery 8. The locking circuit for said relay 7 is established at the intermediate armature switch of this relay before the initial energizing circuit of this relay is broken upon the separation of the contacts 5 and 6 that is effected by the intermediate armature switch of the relay whereby chattering of such relay 7 is avoided and its locking circuit is positively maintained. As long as any relay 7 remains energized the display device 2 individual thereto remains energized in the circuit established at the right hand armature switch of the relay and when each energized relay 7 has its circuit locked the corresponding responsive device 2 will obviously remain energized until its associate relay 7 is deenergized. It is therefore necessary only momentarily to establish circuits at the contacts 1 which are individual to lamps 2 that are selected to glow and be maintained in their set display condition. Thus any character traced upon the transmitting board by touching the stylus 3 (or other suitable terminal structure) to contact buttons 1 outlining such a character will be reproduced by the display devices 2 on the display board if the relay 7 individual to each touched button 1 remains locked after the initial establishment of its initial energizing circuit. When it is desired to efface the displayed character the omnibus restoring key 9 which is common to the locking circuits of all relays 7 is depressed whereby the locking circuits of energized relays 7 are opened and the responsive devices 2 individual to these particular relays are excluded from circuit thereby to efface the previously displayed character.

If the user of the equipment should desire to exclude the displayed lamps 2 from circuit upon the separation of the stylus 3 from the contacts 1 individual to such lamps such a result may be effected by closing the key 10 which is common to the energizing circuits of relays 4. When the key 10 is depressed the relay 4 individual to each button 1 engaged by the stylus 3 is energized owing to the establishment of a circuit which is traceable from the battery 8 through the stylus 3 (or other contacting structure) the button 1 touched by the stylus, the intermediate

armature switch of relay 4 and its normal contact, the engaged contacts 5 and 6 of the relay 7 that is individual to the relay 4, the winding of said relay 7, thence back to the battery, said relay 7 being then energized to establish a circuit for said relay 4 which is traceable from the battery 8 through the stylus 3, the contact button 1 individual to said relay 4, the left hand armature switch of said relay 7 and its contact, the winding of relay 4, the common key 10, back to the battery 8. To prevent the energized relay 4 from chattering, a supplemental but non-locking circuit is established through its winding, said supplemental circuit being traced from the battery 8, the stylus 3, the contact button 1 engaged by the stylus and individual to said relay 4, the intermediate armature switch of said relay 4 and its alternate contact, the winding of said relay 4, the depressed common key 10, to the battery 8, this latter circuit being maintained as long as said button 1 is engaged by the stylus 3, while the common key 10 is depressed, said circuit then being independent of the left hand armature switch of the associate relay 7, this latter relay being immediately deenergized at the left hand armature switch of the associate relay 4, which armature switch is included in the locking circuit of relay 7, chattering of the relay 7 being avoided by opening the circuit at the left hand armature switch of relay 4 when the relay 4 is energized. The responsive device 2 individual to the energized relay 4 is included in a closed circuit at the right hand armature switch of this relay and is immediately excluded from circuit when the stylus 3 is removed from the button 1 individual to this relay for reasons now understood. The relays 4 are desirably made sluggish in operation in order to insure the opening of the circuits of their associate relays 7 at the left hand armature switches of the relays 4.

By means of the system of my invention the relays 7 individual to certain of the lamps 2 may have their armatures held in attracted positions preferably by means of the locking circuits to maintain such lamps in set display condition, while other display lamps 2 may be maintained in display condition only as long as their associate relays 4 are energized as previously explained. Thus a set figure may be displayed upon the display board by means of certain lamps held in set display condition by locked relays 7 while other figures undergoing changes due to the energization and deenergization of relays 4 individual to other lamps may be concurrently displayed. If it should be desired to restore, one by one, the display elements in a set figure this result may be accomplished by depressing the key 10 and touching the corresponding

terminal buttons 1 by the stylus 3, an operation which will be apparent from the foregoing description. In Fig. 1 the circuit portions that are common to the various controlling circuits are indicated by dotted lines. There is but one key 10 which is common to all the energizing circuits of the relays 4 and one key 9 which is included in all of the locking circuits of relay 7.

16 While I have herein shown and particularly described the preferred embodiment of my invention I do not wish to be limited to the precise details of construction and circuit arrangement as changes may readily be made without departing from the spirit of my invention, but having thus described my invention I claim as new and desire to secure by Letters Patent the following:—

1. Display apparatus including a transmitting board that contains a plurality of contact terminals and provided with circuit closing contacting means for coöperation with said terminals to effect operation of the display apparatus; a display board having display elements; circuits individual to the display elements for governing their operation and each having and being individual to a contact terminal upon the transmitting board; electro-magnets for effecting the operation of the display elements and individual thereto and the circuits that govern the same; means for holding the display elements in set display condition upon restoring the altered controlling circuits; and additional electro-magnets individual to the aforesaid electro-magnets and whose energizing circuits are controlled by the aforesaid magnets and which second magnets, when operated, serve to remove control of the first magnets from the second magnets, the second magnets being individual to the display elements and in controlling relation thereto, when operated, to the exclusion of the means for holding the display elements in set display condition.

2. Display apparatus including a transmitting board that contains a plurality of contact terminals and provided with circuit closing contacting means for coöperation with said terminals to effect operation of the display apparatus; a display board having display elements; circuits individual to the display elements for governing their operation and each having and being individual to a contact terminal upon the transmitting board; electro-magnets for effecting the operation of the display elements and individual thereto and the circuits that govern the same; means for maintaining the armatures of the magnets in the positions to which they are moved to maintain the associate display elements in set display condition; and additional electro-magnets individual to the aforesaid electro-magnets and whose energizing circuits are con-

trolled by the aforesaid magnets and which second magnets, when operated, serve to remove control of the first magnets from the second magnets, the second magnets being individual to the display elements and in controlling relation thereto, when operated, to the exclusion of the means for holding the display elements in set display condition.

3. Display apparatus including a transmitting board that contains a plurality of contact terminals and provided with circuit closing contacting means for coöperation with said terminals to effect operation of the display apparatus; a display board having display elements; circuits individual to the display elements for governing their operation and each having and being individual to a contact terminal upon the transmitting board; electro-magnets for effecting the operation of the display elements and individual thereto and the circuits that govern the same; locking circuits for the magnets which are closed thereby when such magnets are energized; and additional electro-magnets individual to the aforesaid electro-magnets and whose energizing circuits are controlled by the aforesaid magnets and which second magnets, when operated, serve to remove control of the first magnets from the second magnets, the second magnets being individual to the display elements and in controlling relation thereto, when operated, to the exclusion of the means for holding the display elements in set display condition.

4. Display apparatus including a transmitting board that contains a plurality of contact terminals and provided with circuit closing contacting means for coöperation with said terminals to effect operation of the display apparatus; a display board having display elements; circuits individual to the display elements for governing their operation and each having and being individual to a contact terminal upon the transmitting board; electro-magnets for effecting the operation of the display elements and individual thereto and the circuits that govern the same; means for holding the display elements in set display condition upon restoring the altered controlling circuits; and additional electro-magnets individual to the aforesaid electro-magnets that serve, when operated, to remove control of the first magnets from the second magnets, the second magnets being individual to the display elements and in controlling relation thereto, when operated, to the exclusion of the means for holding the display elements in set display condition.

5. Display apparatus including a transmitting board that contains a plurality of contact terminals and provided with circuit closing contacting means for coöperation

4
with said terminals to effect operation of the display apparatus; a display board having display elements; circuits individual to the display elements for governing their operation and each having and being individual to a contact terminal upon the transmitting board; electro-magnets for effecting the operation of the display elements and individual thereto and the circuits that govern the same; means for maintaining the armatures of the magnets in the positions to which they are moved to maintain the associate display elements in set display condition; and additional electro-magnets individual to the aforesaid electro-magnets that serve, when operated, to remove control of the first magnets from the second magnets, the second magnets being individual to the display elements and in controlling relation thereto, when operated, to the exclusion of the means for holding the display elements in set display condition.

6. Display apparatus including a transmitting board that contains a plurality of contact terminals and provided with circuit closing contacting means for coöperation with said terminals to effect operation of the

display apparatus; a display board having display elements; circuits individual to the display elements for governing their operation and each having and being individual to a contact terminal upon the transmitting board; electro-magnets for effecting the operation of the display elements and individual thereto and the circuits that govern the same; locking circuits for the magnets which are closed thereby when such magnets are energized; and additional electro-magnets individual to the aforesaid electro-magnets that serve, when operated, to remove control of the first magnets from the second magnets, the second magnets being individual to the display elements and in controlling relation thereto, when operated, to the exclusion of the means for holding the display elements in set display condition.

In witness whereof, I hereunto subscribe my name this 7th day of March A. D. 1914.

WILLIAM A. FRICKE.
